UNITED STATES PATENT OFFICE

2,052,023

TAB AFFIXING MACHINE

John Griesinger, Los Angeles, Calif., assignor to
The National Marking Machine Company, Cincinnati, Ohio, a corporation of Ohio

Application June 8, 1931, Serial No. 542,885

13 Claims. (Cl. 112—104)

The objects of my invention are to provide a tab affixing machine for sewing tabs to laundry articles, which machine is capable of affixing said tabs as rapidly as the operator can place laundry articles in position for tabbing; or in other words, so that the total output of the tabbing machine in a given period is governed by the speed of the operator in placing the laundry articles in position to receive tabs, and substantially no delay is experienced by the operation of the machine in affixing the tabs to the articles.

A further object is to affix the tabs to the articles in such a manner that they will withstand all of the usual laundrying operations without becoming detached from the articles, and yet may be readily and easily removed when desired.

A further object is to provide new and useful means for cutting the tab affixing thread into short lengths, drawing both end portions thereof through a tab and a laundry article, and then firmly affixing said end portions of the thread to the tab.

A further object is to provide new and useful means for sewing a tab to a laundry article in such manner that only a thin flat surface of the tab rests flat against a small part of the margin of the laundry article, so that the tab does not interfere with the usual ironing process nor leave an objectionable mark thereon after the removal of the tab; and

Further in this connection to provide a machine which will sew the tab to the article and leave the central portion of the thread clearly visible across the outer face of the tab, so that it is easily seen and easily severed to remove the tab.

A further object is to provide new and useful means for cutting the tabs and folding them in position for securely affixing the tabs to the end portions of the thread.

A further object is to provide improved means for automatically applying identification marks to the tabs just prior to connecting them to the articles.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of my improved machine partly in section and with parts broken away to show the operating mechanism.

Figure 2 shows a front end elevation of same

partly in section to illustrate the needle operating and presser foot device.

Figure 3 shows a rear end elevation of same showing the interior construction.

Figure 4 shows a detail side elevation illustrating a portion of the mechanism for manually starting and automatically stopping the operation of the machine.

Figure 5 shows a top or plan view of the same with the manual starting mechanism removed.

Figure 6 shows a detail side view partly in section illustrating the clutch, the disk and lever and a portion of the manual starting mechanism.

Figure 7 shows a rear end elevation of the structure shown in Figure 4, parts being broken away to show the clutch lever.

Figure 8 shows a detail view illustrating the clutch mechanism and starting disk in released position.

Figure 9 shows a front elevation illustrating the needle threading mechanism.

Figure 10 shows a detail view partly in section illustrating the thread cutting and clamping mechanism.

Figure 11 shows a detail side view of the thread clamping mechanism of the thread pick-up device with the jaws in open position.

Figure 12 shows a similar view with the jaws in closed position clamping the thread.

Figure 13 shows a detail top view of the mechanism for holding the short section of thread and for advancing it to position for being threaded into the needles.

Figure 14 shows a side elevation of same and illustrating a portion of the cam for operating it.

Figure 15 shows a detail, vertical, sectional view illustrating a means for holding the central portion of the thread against the under side of the tab to prevent longitudinal movement during the time when the needles are drawing the ends of the thread upwardly through the tab and article.

Figure 16 shows a top or plan view of a tab of the kind employed with my machine. The dotted lines illustrate the connected tabs forming a continuous strip.

Figure 17 shows a face view of a completed tab; and

Figure 18 shows the opposite side thereof.

Figure 19 shows one of my improved tabs applied to a laundry article in its completed form.

Figure 20 shows a sectional perspective view of same on the line 20—20 of Figure 19.

Figure 21 shows an isometric view illustrating

the mechanism for bending the side margins of the tab down over the end portions of the thread and the body of the tab.

Figure 22 shows an isometric view illustrating 5 the mechanism for advancing the strip of tab material, and also illustrating the mechanism for drawing the end portions of the thread rearwardly over the face of the tab and for holding the thread in such position during the time the 10 side margins of the tab are being folded down over the thread and the tab.

Figure 23 shows a transverse sectional view 15 on the line 23—23 of Figure 15, illustrating the manner in which the central portion of the thread 15 is clamped to the tab during the upward movement of the needles.

Figure 24 shows a side elevation of the die for forming an identification mark on the tabs.

Figure 25 shows a top or plan view of same, 20 the face of the die being indicated by dotted lines.

Figure 26 shows a rear end elevation of same.

Figure 27 shows a detail front view illustrating the tab cutting shear member and the cam devices for operating it.

25 Figure 28 shows a side elevation of same.

Figure 29 shows a front elevation of the means employed for bending the end margin of the tab horizontally.

Figure 30 shows a side elevation of same.

30 Figure 31 shows a top or plan view of the means for applying yielding tension to the tab strip.

Figure 32 shows a side elevation of same with the tab strip in position therein.

35 Figure 33 shows a front elevation of same with the tab strip in position.

Figure 34 shows a front elevation of the needle supporting bar and the cam for actuating it.

Figure 35 shows a side elevation of same.

40 Figure 36 shows a front elevation of the device for bending the end margin of the tab forwardly over the body of the tab and the cams for operating it.

Figure 37 shows a side elevation partly in section of the same.

45 Figure 38 shows a front elevation of the device for bending upwardly the side margins of the tabs and the cam devices for operating the same.

Figure 39 shows a side elevation of same.

50 Figure 40 shows a front elevation of the tab marking die and the means for operating it.

Figure 41 shows a side elevation of the same.

55 Figure 42 shows a front elevation partly in section illustrating the presser foot and the means for operating it.

Figure 43 shows a side elevation of same.

Figure 44 shows an enlarged, detail, sectional view illustrating the lower end of the device for bending the end margin of the tab down over the 60 face of the tab.

65 Referring to the accompanying drawings, I have used the reference numeral 50 to indicate generally the frame of the machine. Contained within the frame is an electric motor 51 for driving the upper power shaft 52 and the lower power shaft 53. These power shafts are driven from the motor through the worm gear 54, pinion 58 in mesh with the pinion 56 on the lower power shaft, and a small pinion 57 in mesh with the pinion 55 on the upper power shaft.

70 These power shafts are intended to be operated only through one complete cycle necessary to affix a tab to a laundry article, and are intended to then be stopped until the operator 75 can place a new article in position to be tabbed.

For this purpose I have provided the following mechanism:

Mounted upon a shaft 59 is a worm gear 60 in mesh with the worm gear 54 so that it is constantly driven during the operation of the motor. Connected with the gear 60 is a cylindrical drum containing in its interior a notched clutch disk 61.

This clutch disk 61 is adjacent to and in line with the pinion 58, and carried by this pinion 10 is a clutch lever 62 arranged, when in one position as shown in Figure 7, to be engaged by an adjacent notch of the clutch disk 61, so that the clutch device will carry the pinion 58 around with it, and when this clutch lever 62 is moved to the 15 position shown in Figure 8, it will be disengaged from the notched clutch disk 61 so that the pinion 58 will not be driven. The clutch lever 62 is provided with a spring 63 for normally holding it in the position shown in Figure 7.

20 Mounted upon the rear side of the pinion 58 is a rearwardly extended cam 64, and this cam is designed to operate a stop disk 65 rotatively mounted upon a shaft 66 at right angles to the shaft 59.

25 This stop disk 65 is provided with notches 67 and is so shaped and arranged that as the cam 64 is rotated, it will engage the material at one side of the adjacent notch 67 and move the stop disk to position where the approaching clutch 30 lever 62 will engage the disk 65, and thus trip the clutch mechanism and thereby stop the movement of the power shafts, but when the clutch lever 62 engages the disk 65, the cam 64 will have rotated past the disk 65.

35 For starting the power shafts I have provided on the disk 65 a series of pins 68. Pivoted near the front of the machine frame is a lever 69 to which a rod 70 is pivoted, and this rod carries a notched bar 71 normally held at its rearward 40 limit by a spring 72.

45 By pulling forwardly upon the lever 69, the notched bar 71 engages one of the pins 68 of the disk 65 and moves the disk far enough to bring one of the notches 67 of the disk 65 into the path of the clutch lever 62, so that the power shafts are again operatively connected with the motor.

50 For the purpose of operating the power shafts by hand when desired, I have provided a hand wheel 73 fixed to a shaft 74, which shaft has a pinion 75 at its rear end in mesh with the pinion 58.

55 The tabs shown in Figures 3, 16, 17 and 18 are formed of thin metal such for instance as zinc, and are easily bendable and non-resilient so that they will retain the shape to which they are bent. These tabs are formed in continuous strips as shown in Figure 3, and each tab in the strip comprises a body portion 76 having two 60 spaced apart openings 77 near one end. At its sides are marginal edge portions 78, and at the end opposite from the openings is a marginal 65 end portion 79, and when applied the marginal edges 78 are folded over the body and finally the marginal edge 79 is folded over the body and the previously folded side margins, as shown in Figure 18.

70 This strip of tabs is inserted through an opening in the back of the machine, as shown in Figure 3, and extends straight forwardly through the machine through a groove 80, as shown in Figure 33.

75 For yieldably holding this strip of tab material to position, I have provided a spring 81 75

shown in Figures 32 and 33, which normally presses downwardly upon the tabs. This spring may be elevated by operating the small lever 82 connected to an eccentric 83 below the spring. 5 The end of the spring beyond the eccentric is secured in position by a screw 84.

The first operation performed by the machine upon the tab strip is the bending of the side margins 78 upwardly, and this is done before the 10 end of the tab strip reaches the point where the tabs are affixed to the articles.

The means for bending these margins upwardly comprises a block 85, shown in Figure 38, having two upwardly extended arms 86. This 15 block is carried by a sliding frame 87 engaged by a cam 88 on the lower power shaft 53, and during the time that this block 85 is being moved upwardly a bar 89 is moved downwardly into position resting against the upper surface of the 20 tab strip to prevent it from moving upwardly. This bar is moved downwardly by a cam 90 on the upper power shaft 52, and it is moved upwardly after it has performed its function by means of a sliding bar 91 moved downwardly by 25 a cam 92 on the upper power shaft 52. Each of these bars 91 and 89 is formed with a rack 94, and mounted on the stationary support between said racks is a pinion 95 in mesh with both racks, and this device causes a downward 30 movement of the bar 89 to effect an upward movement of the bar 91, and vice versa.

In this connection it may be stated that this same idea of using two cams on the same shaft, one for effecting the movement of the bar in one direction, and one for effecting movement of the bar in the opposite direction, by means of this rack and pinion arrangement, is employed in numerous places throughout this machine, and hence it is believed unnecessary to describe 40 it in detail as applied to each of the several devices with which it is employed.

The next thing that is done to the tab strip after the side margins are folded is to move it forwardly one tab space, and this is accomplished 45 by the mechanism illustrated in Figure 22, as follows:

On the lower power shaft there is a wheel 96 having a cam groove 97 in which there is a roller 98. This roller is connected to a bar 99 which 50 is fixed to two sliding rods 100. Carried by these rods is a rod 101 to which is pivoted a lever 102. The front end of this lever is normally inclined downwardly and in position to engage the up-standing marginal edges of the adjacent tab, so 55 that when the rods 100 are moved forwardly, the tab strip is advanced one tab length, and when the rods 100 move rearwardly, the lever 102 slides over the tabs.

After a tab is presented to position to be affixed 60 to an article, then the article is placed on top of the tab over the openings therein. Then the thread laying device is placed in position over the tab to receive the threads. This thread laying device includes an arm 103, which is more 65 fully described hereafter.

The next operation of the machine is to move the presser foot down into position for holding the arm 103, the garment and the tab firmly 70 together, while the end portions of the thread are being pulled upwardly through them. The presser foot is indicated generally by the numeral 104, and is mounted upon two rods 105, which are yieldably held downwardly by the 75 springs 106.

The presser foot is moved forcibly upwardly at the proper time in the cycle of movement of the machine by means of a lever 108. Its forward end engages a part of the presser foot and its rear end is engaged by the bar 109 operated by the cam 107 on the upper power shaft 52.

For cutting off the individual tabs from the tab strip I have provided the mechanism shown in Figures 27 and 28, and which comprises a pivoted cutter blade 111 normally above the tab 10 strip, pivotally connected to an arm 112 on a shaft 113. Fixed to this shaft are two arms 114 and 115, to engage respectively the two cams 116 and 117. This blade co-operates with a fixed straight edge on the machine frame not shown, to operate in severing the tab strip in an ordinary manner.

After the tab has been separated from the tab strip in the manner just described, the rear end portion of the tab is bent upwardly to a substantially upright position prior to its being folded over the tab and the thread.

The means for causing this upward bending of the rear end of the tab is illustrated in Figures 29 and 30, and comprise a folder bar 118 pivoted to a shaft 119, and having a pivotal connection with the arm 120 on the shaft 121. Fixed to this shaft 121 are the arms 122 and 123 to engage respectively the cams 124 and 125 fixed to the lower power shaft. These cams are so arranged upon the power shafts that the folder bar 118 will be moved upwardly immediately after the tab has been separated from the tab strip by the cutter blade 111, and then the folder bar 118 is moved downwardly out of the path of travel 35 of the tab strip.

For forming identification marks upon the tab I have provided a marking device comprising a base member 126 and a top member 127 pivotally connected to the base member. The top 40 member is yieldably held at its upward limit by a spring 128 and one or both are provided with impression making means, such as dies 129. This marking device is removably placed within the machine frame as shown in Figures 1 and 2, so 45 that a new one can be substituted for each separate individual's laundry articles.

For operating the die I have provided a bar 130 which is moved up and down at the proper time by the cams 131 and 132 on the upper power 50 shaft 52, as shown in Figures 40 and 41.

After the end portions of the thread have been laid in position over the top of the tab, it is desired to fold the side margins inwardly and press them firmly down, one over each of said 55 thread portions. For accomplishing this purpose I have provided a frame 140 slidably supported and having two cam engaging surfaces thereon. Extended through an opening in the frame is the lower power shaft 53, and on this shaft is 60 a cam 141, which during its revolution will move the frame 140 upwardly and downwardly by engagement with the frame members above and below the shaft 53.

Pivottally supported below the frame 140 are 65 two levers 142, which extend upwardly through the slots in the frame 140 and inwardly over the top of the frame and terminate in presser heads 143.

In each of these levers 142 is a curved slot 70 144 through which a pin 145 is extended so that the pin and slot will guide the movement of the lever 142. When the frame 140 moves downwardly, the pin and slot 145 and 144 will cause the presser heads 143 to move toward each other 75.

and downwardly, and will firmly press the side margins of the tab over the body of the tab and against the threads thereon. After the side margins have been bent as just described, the end 5 margin of the tab is bent over the thread portions and previously folded side margin portions of the tab by the following mechanism:

It is important that means be provided for bending this margin down over the previously 10 folded side margins and firmly pressing it to said position, and this mechanism is shown in Figures 36, 37 and 44, and comprises a slide bar 133 operated to raise and lower by cams 134 and 135 similar to the ones before described. At the lower 15 end of the bar 133 is a relatively flat surface at 136 and pivotally mounted in the under end of the bar is a folding member 137 having its forward face inclined upwardly and forwardly at 138, and a cushioning spring 139 yieldably 20 holds the lower end of the folding member 137 forwardly.

In operation with this part of the device, and assuming that the bar 133 is moved downwardly toward a tab with its rear margin turned straight 25 up or inclined either way from a straight vertical line, then the inclined surface 138 will engage its upper edge and slowly as the bar 133 descends bends the margin of the tab forwardly and downwardly, or when the part 136 engages 30 it, it will firmly press it against the body of the tab.

The needles employed in my machine are of the crochet variety having thread receiving notches therein as shown in Figure 14. There 35 are two needles 145 and they are fixed to the bar 147 in spaced apart relation with the thread receiving notches at their front sides. This bar 147 is operated by means of a bell crank lever 148 having one arm thereof extended into the cam grooved wheel 149 on the upper power shaft 52.

The thread to be used in my machine is mounted upon the spool 150 and passes over a thread tension device 151 of the kind ordinarily 45 used on sewing machines, and extends through a cylinder casing 152 at the front of the machine below the needles.

For holding this thread in position, I have provided the device illustrated in Figure 10 consisting of a stationary body 153 having a stationary cutter blade 154 fixed to it. Slidably mounted within the body 153 is a bar 155 having at its upper end a cutter blade 156 to co-operate with the blade 154, and also having a thread gripping arm 157, and slidably mounted 55 within the frame 153 is a coacting thread gripping bar 158 yieldably held upwardly by a spring 159.

For operating the slide bar 155 I have provided 60 a cam 160 on the lower power shaft 53, and the parts are so arranged that when the bar 155 moves downwardly, it will sever the thread between the cutters 156 and 154, and at the same time will clamp the unsevered portion of the 65 thread between the clamping members 157 and 158.

Assuming that the end portion of the thread on the spool is clamped in the thread holder, as shown in Figure 9, the thread will then be 70 picked up and carried to position for threading the needles as follows:

Mounted upon the lower power shaft 53 is a thread pick-up arm 161 extended radially within the casing 152. To its outer end is fixed a plate 162 and connected with this plate is a slide 75

plate 163. The plate 163 is supported by a screw 164 in the slot 165 in the plate 163. The plate 162 has at its rear end an outwardly extended thread gripping jaw 166 having a notch 167 therein and the slide gripping member 163 has 5 a lug 168 to enter the said notch 167.

A spring 169 is provided for yieldably holding the sliding gripping member to gripping position and it is withdrawn from the gripping position by means of a roller 170 fixed to said 10 sliding member and operated by cams 171 and 172 on the casing 152 located at the point where it is desired to have the thread pick-up device released from the thread.

The operation of this part of the device is as 15 follows:

The thread pick-up device in its travel will have its gripping jaws open, as shown in Figure 11, when it passes the thread held in the holder 153, see Fig. 9. As soon as the roller 170 passes the cam 172, the thread gripping jaws will close, as shown in Figure 12, and at the same time the thread holder will release the thread as before described, thereupon a portion of the thread will be drawn through the released thread 25 holder and carried upwardly toward the right, as shown in Figure 9, until the roller 170 strikes the cam 171, whereupon the thread will again be released at the same time the cam 160 will operate the thread cutter 155, leaving a severed 30 section of thread to be picked up by the needles, as shown in Figure 9.

After the thread has been severed in the manner just described, it is laid into the needle threading mechanism, which, as shown in Figures 13 and 14, comprises a body portion 173 pivoted at its lower end to swing forwardly and rearwardly and having a thread receiving notch 174 at its upper end. It is also provided with transverse grooves 175 across its upper end. 40

Pivoted to the body 173 is a lever 176 extended forwardly and then upwardly and provided at its upper end with thread gripping springs 177 designed to operate in the grooves 175. This lever 176 is moved upwardly and rearwardly to 45 grip the thread in the grooves 174 by means of a roller 178 carried by it and engaged by a cam 179 on the lower power shaft 53, and it is moved forwardly and downwardly by the spring 180.

When the springs 177 have been moved to 50 position for gripping the thread, then the body 173 containing the thread is forced rearwardly by having the lever 176 engage the lug 181 on the body 173. This moves the thread rearwardly into the path of the notched needles 55 and when the notched needles move upwardly, the thread will be threaded into the notches and picked up by the needles.

After the thread has been picked up by the 60 needles and carried by them up against the under surface of the tab, then it is desirable to apply pressure to the central portion of the thread against the tab, so that the friction of the end portions of the thread passing through the needles will not cause any lengthwise movement of the body of the thread, and for this purpose I have provided a sliding block 182 in which is carried a spring 183, which spring has one end extended upwardly into an opening in the machine frame immediately surrounding the 65 place where the needles pass through the frame, as shown in Figures 15 and 23.

The portion of the machine frame adjacent to this needle opening is provided with a curved notch 184 to serve as a guide for the spring 183. 75

A spring 185 is provided for normally holding the block 182 at its forward limit, and this block is moved rearwardly by an arm 186 on the body 173. The operation of this part of the mechanism is as follows:

When the thread is being drawn upwardly through the tab and the article being tabbed, the spring 183 presses upon the central portion of the thread, as clearly shown in Figure 23. When, however, the thread is being placed in the needles and the needles are moving upwardly toward the tab, this spring 183 is held out of the path of the needles and thread by the arm 186 engaging the block 182. The position of the spring when thus held is shown by dotted lines in Figure 15.

For laying and firmly holding the end portions of the thread in position on top of the tab, so that the side margins of the tab may be folded over these firmly held end portions of the thread, I have provided the following mechanism:

The thread laying lever 103 before mentioned is pivotally supported at 187 upon one of the rods 100, as shown in Figure 22. Its forward end is arranged in position directly over the tab strip and it is provided with two thread openings 188 designed to be positioned directly over the thread openings of the tab on which it is placed. A spring 189 is provided for yieldably holding the front end of the lever 103 into pressing engagement with the top of the tab.

For elevating the thread laying lever when desired, I have provided a sliding bar 190 operated by a cam 191. This bar 190 is provided with a pin 192 to engage a lever 193 fixed to the frame and having its forward end designed to engage and elevate the presser foot, as shown in Figure 22. The operation of this thread laying mechanism is as follows:

After the needles have been drawn upwardly through the tab, the article and the openings 188 in the lever 103, and as soon as the needles have passed above the openings 188, then the rod 100 is moved rearwardly by its cam device, and during this rearward movement the spring 189 holds the front end of the lever 103 downwardly against the top of the tab and carries the ends of the thread to a point spaced beyond the rear end of the tab.

During the time that the thread end portions are still being yieldably held against the tab, the side margins of the tab are folded over, and the thread ends are not released by the thread laying device until after the threads have been firmly positioned under and clamped down by the side margins of the tab.

My improved machine has been thoroughly tested in practical operation and I have demonstrated that it can be run at high speed, so that as fast as an operator can select the articles to be tabbed and place them in position upon the machine, the operation of sewing the tab is practically instantaneous, so that no delay is caused by the operation of the machine.

I have also found that the threads are accurately laid in position under the side margins, and there firmly clamped by the side margins, and then when the end margin is bent over, a double lock is formed on the thread, which, in practice has been demonstrated, attaches the tabs to the garments firmly and securely enough to withstand all of the ordinary laundrying and ironing processes without becoming detached therefrom.

I have demonstrated that with tabs of the character herein disclosed, and sewed to the edge

portions of the garments, as shown, the articles may be passed through the ordinary ironing processes without leaving any appreciable depression or mark on the garment after the tab is removed.

After the laundry articles with the tabs thereon have passed through the laundry operation, the tabs may be removed very easily and readily by an operator, because a portion of the thread is readily visible across the end of the tab and a knife may be inserted between the tab and the thread to cut it off, whereupon the tab can be readily removed.

I claim as my invention:

1. In a machine of the class described, the combination of a means for supporting a tab and an article to which the tab is to be attached, two spaced apart needles, means for moving them through the article and tab, means for threading both needles, means for drawing the needles back through the article and tab to thereby draw both ends of the thread through the article and tab, means for laying the end portions of the thread against the tab and means for folding portions of the tab over the thread.

2. In a machine of the class described, the combination of a means for supporting a tab and an article to which the tab is to be attached, two spaced apart needles, means for moving them through the article and tab, means for threading both needles, means for cutting the thread, and means for drawing the needles back through the article and tab to thereby draw both ends of the thread through the article and tab, and means for folding a portion of the tab over a portion of the thread.

3. In a machine of the class described, the combination of two spaced apart movable needles having thread receiving notches therein, means for threading a short piece of thread into said notches, comprising a movable thread carrying member having a notch to receive a short section of thread, means for moving said notched member to position for placing the thread held therein in the path of the movement of the needles so that it will enter the notches of both needles, and means for applying yielding pressure to the central portion of the thread to prevent longitudinal movement of the thread.

4. In a machine of the class described, the combination of two spaced apart movable needles having thread receiving notches therein, means for threading a short piece of thread into said notches, comprising a movable thread carrying member having a notch to receive a short section of thread, means for moving said notched member to position for placing the thread held therein in the path of the movement of the needles so that it will enter the notches of both needles, and spring arms to engage the thread in said notch of the thread carrying member.

5. In a needle threading device, the combination of a thread holder, means for operating it to grip or release a thread, a thread pick-up device, means for moving it relative to the thread holder, said pick-up device having jaws for gripping or releasing a thread, means for operating said jaws to grip a thread when the pick-up device passes said holder, means for operating the jaws to release the thread after it has traveled a short distance, means for cutting off a section of the thread after it has been carried a short distance beyond said holder, two spaced apart needles having thread receiving notches, a movable thread carrier having a notch therein to

- receive the thread from the pick-up device, spring actuated thread engaging arms to engage the thread in said notch in the carrier, and means for moving the movable thread carrier with the 5 thread to position for projecting the thread into the path of the needles to cause it to enter the notches therein when the needles are elevated.
6. In a needle threading device, the combination of a thread holder, means for operating it 10 to grip or release a thread, a thread pick-up device, means for moving it relative to the thread holder, said pick-up device having jaws for gripping or releasing a thread, means for operating said jaws to grip a thread when the pick-up device 15 passes said holder, means for operating the jaws to release the thread after it has traveled a short distance, means for cutting off a section of the thread after it has been carried a short distance beyond said holder, two spaced apart 20 needles having thread receiving notches, a movable thread carrier having notches therein to receive the thread from the pick-up device, spring actuated thread engaging arms to engage the thread in said notches in the carrier, means for moving the movable thread carrier with the 25 thread to position for projecting the thread into the path of the needles to cause it to enter the notches therein when the needles are elevated, means for applying yielding pressure to the 30 thread to prevent its longitudinal movement, and means for relieving said pressure.
7. In a machine of the class described for attaching a bendable tab to a fabric, the combination of means for drawing two ends of a short 35 thread through the tab and fabric, a thread laying device for engaging both end portions of the thread, means for moving the end portions of the thread to position in spaced apart relation over and against the surface of the tab.
- 40 8. In a machine of the class described for attaching a bendable tab to a fabric, the combination of means for drawing two ends of a short thread through the tab and fabric, a thread laying device for engaging both end portions of the 45 thread, means for moving the end portions of the thread to position in spaced apart relation over and against the surface of the tab, and means for yieldably holding the thread against the tab to securely hold the thread in position during 50 the thread laying movement.
9. In a machine of the class described for attaching a bendable tab to a fabric, the combination of means for drawing the ends of a short

thread through the tab and fabric, a thread laying device for engaging both end portions of the thread, means for moving the end portions of the thread to position in spaced apart relation over and against the surface of the tab, and 5 means for folding one side margin of the tab over each of said thread portions.

10. In a machine of the class described for attaching a bendable tab to a fabric, the combination of means for drawing two ends of a short 10 thread through the tab and fabric, a thread laying device for engaging both end portions of the thread, means for moving the end portions of the thread to position in spaced apart relation over and against the surface of the tab, means 15 for folding one side margin of the tab over each of said thread portions, and means for folding the end margin of the tab over the previously folded side margins and over both of said thread portions. 20

11. In a device of the class described for attaching a bendable tab to a fabric, the combination of means for extending the end portions of a thread through the tab and fabric, means for laying said end portions of the thread one on 25 each side of the tab, means for folding each side margin of the tab over one of said thread portions, and means for folding the end margin of the tab over the previously folded side margins. 30

12. In a machine of the class described for attaching a bendable tab to a fabric, means for supporting the tab, means for folding one margin of the tab upwardly, and means for folding said upturned margin downwardly over the body 35 of the tab, comprising a vertically movable bar having its lower end substantially parallel with the tab, a pivoted tab engaging member at the lower end of the bar with one face inclined upwardly and over the body of the tab being operated on, and a spring for yieldably holding said 40 tab engaging member toward the tab being operated on.

13. In a machine of the class described, for attaching a bendable tab to a fabric, means for extending two spaced apart portions of a thread 45 through the fabric to which the tab is to be attached, means for laying said thread portions over and against the surface of the tab, means for folding the side edges of the tab over said thread portions, and means for folding an end 50 portion of the tab over the previously folded side edges.

JOHN GRIESINGER.
